OPERATING MECHANISM FOR THE THREAD-CARRIER RAILS OF FLAT FRAMEWORK KNITTING MACHINES

Anton Loimann, Chemnitz, Germany

Application January 14, 1936, Serial No. 59,129
In Germany January 9, 1935

9 Claims. (Cl. 66—126)

This invention relates to operating mechanisms for the thread-carrier rails of flat framework knitting machines the catch-bar of said rails being moved by the aid of a flexible driving chain laid around several rollers that are adjustable in 5 longitudinal direction of the machine.

In known constructions of this kind the smallest possible path of motion for the catch-bar for the respective thread-carrier rail is defined by the size of the guide-rollers for the driving chain. 10 This is due to the fact that the ascending part of said chain must always remain at a distance from the descending part said distance being greater than twice the diameter of a guide-roller. 15 For this reason the path of motion of the said catch-bar cannot be reduced to an extent, as is for instance possible when knitting the front part or toe portion of a stocking. Thus, in known driving devices for machines of the 20 present kind the so-called brakes which serve for the transmission of motion from the catch-bar to the thread-carrier rail cannot be dispensed with.

In order to obviate this disadvantage, according to my invention the sprocket-wheels for the 25 driving chains which serve for guiding the latter from the one to the other supporting slide are so displaced with respect to each other that said sprocket-wheels during displacement of said slides into their shortest distance from each other 30 will move past each other or at least come into co-axial position.

In the accompanying drawings which form part of this specification several exemplifications 35 of the construction of the novel operating mechanism are shown, Fig. 1 being an elevation of the improved driving and operating organs of a flat framework knitting machine provided with the present mechanism, Figs. 2 and 3 being plan views of several arrangements of sprocket-wheels for the machine, Figs. 4 and 5 an elevation 40 and plan view, respectively, showing another arrangement of sprocket-wheels, Fig. 6 a plan view of another novel construction of the operating mechanism, and Fig. 7 an explanatory diagram illustrating the mode of operation of said mechanism.

Referring more particularly to the drawings, the ends of the driving chain 4 having one or 50 more tracks are fixed at the points 2 and 3 to the slur-cock rail 1 or a driving rod connected thereto by means of a friction-clutch. The driving chain 4 is laid around a plurality of sprocket-wheels 5, 6, 7, 8, 9 and 10. The sprocket-wheels 55 5 and 6 are mounted on a slide 11 horizontally

displaceable on the machine frame so that the portion of the chain 4 extending from the one inner sprocket-wheel 5 to the other inner sprocket-wheel 6 is directed perpendicularly to said slur-cock rail 1. In a similar manner the sprocket-wheels 7 and 8 are mounted on a second slide 12 also horizontally displaceable on the machine frame, so that the portion of the chain 4 which is intermediate the sprocket-wheels 7 and 8 is likewise positioned perpendicular to the rail 1. The sprocket-wheel 9 is supported at the free end of a double-armed cranked lever 14 pivoted at 13 to the slide 12, as shown in Fig. 1. The longer arm 15 of the lever 14 carries a roller 16 engaging with a curved track 17 fast on the machine frame, so that the sprocket-wheel 9 upon displacement of the slide 12 will be adjusted 10 with respect to the latter. The curved track 17 should be of proper conformation to maintain the driving chain 4 in stretched condition during 20 every adjustment between the slides 11 and 12. The sprocket-wheel 10 is mounted on the slide 12.

The difference in the height of the sprocket-wheels 5 and 8 is preferably chosen somewhat greater than the operating stroke of the slur-cock 25 rail 1. The slides 11 and 12 are connected in known manner with an adjusting device in such a way that the latter will determine the adjustment of said slides 11 and 12 and simultaneously therewith their distance from each other.

The portion of the driving chain 4 positioned between the sprocket-wheels 6 and 7 carries at its center in the known manner a pivot 20 carrying a sliding block 21. The latter is displaceable within a vertical guide 22 fixedly connected 30 to the catch-bar 23 and through the latter detachably from the slur-cock rail 1. A brake for the transmission of power from the slur-cock rail 1 to the bar 23 will not be necessary. It may, however, be preferable to provide for such transmission of power a friction clutch which does not need to be exactly adjusted upon a definite amount of power to be transmitted as is the case when employing a brake, said friction clutch operating only if during the transmission of 40 driving motion to the thread-carrier rail a fracture of some of the organs of the machine is liable to arise. The aforementioned friction clutch; however, should be used only in case such a clutch is not present between the slur-cock 45 rail 1 and the driving rod.

As the portions of the driving chain positioned on the one hand between the sprocket-wheels 5 and 6 and on the other hand between the sprocket-wheels 7 and 8 are on different sides of the 55

portion of said chain stretching between the sprocket-wheels 6 and 7, the slides 11 and 12 may be moved towards each other in such a manner that the chain 4 extends in a closed path 5 from the sprocket-wheel 5 as far as to the sprocket-wheel 8. In order to ensure this, the sprocket-wheels 6 and 7 must be arranged to permit motion of one wheel past the other without any obstruction arising during adjusting the 10 slides 11 and 12 into shortest distance between each other. This may be accomplished in a most convenient way by placing the sprocket-wheel 7 with its axis above the axis of the sprocket-wheel 6, the distance between said two axes being 15 equal to the sum of the outer diameters of said sprocket-wheels, in order to provide a free path of motion above the sprocket-wheel 6 for the sprocket-wheel 7 in the proper relative position of the slides 11 and 12, and in order to attain 20 horizontal or approximately horizontal position of the portion of the chain 4 stretching between said sprocket-wheels 6 and 7. If the sprocket-wheels 6 and 7 are equipped in this case with relatively widely projecting guide-disks or 25 teeth, the driving chain 4 should be constructed with three tracks, the two outer tracks co-operating each with one set of sprocket-wheels 5, 7 and 8 and the middle track with the sprocket-wheel 6. Upon moving the slides 11 and 12 towards each other the projecting teeth on the sprocket-wheel 6 will pass between the teeth on the two sprocket-wheels 7. If, on the other hand, the sprocket-wheels 6 and 7 are not provided with properly projecting parts, or if the sprocket-wheels 7 are positioned at a proper height above 30 the wheels 6, a chain with a single track and a single set of sprocket-wheels 5, 6, 7 and 8 may be used as shown in Fig. 3. In this case also a cable, rope, belt or the like may be used instead 35 of the chain 4.

In many instances, and more particularly in case the portion of the chain 4 running from the sprocket-wheel 6 to the sprocket-wheel 7 is stretched out in exactly horizontal position and 40 the roller 9 so arranged that said chain runs also in stretched condition from the wheel 8 to the wheel 10, the length of the curved track 17 may be reduced to extend only through a short distance, said track now solely serving the purpose 45 of keeping the chain 4 in stretched condition while the wheel 7 is moved above and past the wheel 6 in the respective position of the slides 11 and 12. This condition may also be attained by means of a fixed stop with which the arm 14 50 of the cranked lever 14, 15 comes into engagement at the proper time.

From the aforesaid explanation it follows that with a definite relative adjustment of the slides 11 and 12, the guide 22 and the thread-carrier rail will be adjusted, upon each reciprocating motion of the slur-cock rail 1 or of the driving rod connected thereto, along the horizontal distance between the portion of the chain extending from the wheel 5 to the wheel 6 and the portion 65 of the chain extending from the wheel 7 to the wheel 8. This is due to the fact that the slide block 21 is moving up and down idle within its guide 22. If, however, the pivot 20 is moving from the wheel 6 towards the wheel 7 or in opposite direction, said pivot will impart positive motion to the guide 22 and the thread-carrier rail connected thereto. If the two slides 11 and 12 are moved towards each other to an extent 70 that the chain 4 reaches in stretched condition 75 from the wheel 5 to the wheel 8, there will be no

adjustment whatever of the guide 22 upon reciprocating motion of the slur-cock rail 1. Thus, by adjusting the slides 11 and 12 the adjustment of the guide 22 and of the guide block 21 therein may be reduced to an extent necessary 5 for knitting the toe portion of a stocking, so that the aforesaid operating mechanism will be practicable without the use of any kind of brakes, which had so far been regarded as being indispensable.

If no intrinsical value is placed on the possibility of reducing the stroke of the thread-carrier rail as far as to zero, a shortening of the path of driving motion of the respective thread-carrier rail may be attained in many cases in a better 10 way, as compared with the known arrangement of rollers. For this purpose a double-tracked chain 4' as shown in Figs. 4 and 5 is carried over two co-axial sprocket-wheels 5' on the slide 11', thereupon only over one sprocket wheel 6' on 15 the same slide and thereupon over the sprocket-wheel 7' and two co-axial sprocket-wheels 8', all three on the slide 12', the wheel 6' running in a track different from that for the wheel 7', consequently permitting passage of one wheel past 20 the other during moving together the slides, so that said wheels will finally come into co-axial position. In this case the diameter of the sprocket-wheels 6' and 7' must be chosen as small 25 as possible.

Instead of keeping the chain 4 in stretched condition by a positive motion of the tension roller 9 whenever the sprocket-wheels 6 and 7 shown in Fig. 1 pass one above the other, it would also be possible, in order to attain the same 30 result, to move upward and downward one or both slides 11 and 12 at the end of their path of motion obliquely to the direction of motion of the slur-cock rail 1, eventually by means of a curved track. If the axes of the two sprocket- 35 wheels 6 and 7 have moved, one above and past the other, the portions of the chain, which had so far been on said wheels 6 and 7 will be stretched, and now the sum of those portions of the chain is increased that are freely stretched 40 out between the fixed ends 2 and 3 of the chain, the portion of the chain that had previously been positioned between the wheels 6 and 7 having now come outside of said wheels. The influence of the first mentioned condition prepon- 45 derates at the moment the axes of the sprocket-wheels 6 and 7 are just in position one perpendicularly above the other. If the slides 11 and 12, however, are further moved towards each other the lengthening of the horizontal portion 50 of the chain will be more and more noticeable. This change in the tension of the chain must be taken into consideration, when using a ten- 55 sion roller 9 for positive adjustment of the chain as well as when moving the slides 11 and 12 in 60 transverse direction.

As regards the special shape of the sprocket wheels 5, 6, 7, 8, and 9 it may be remarked that these wheels may also be made more of a cylindrical form, that is, in the form of a roller or 65 the like.

Instead of the closed guide-member 22 as shown in Fig. 1 preferably a guide may be used that is open not only at its under end, as known, but also at its upper end, as shown in Fig. 6; 70 in this case the catch-member made in the form of a guide-roller will move out of its open guide in upward or downward direction, whenever during reciprocating motion of the chain 4 said roller comes in contact with a vertically directed 75

portion 25 or 26 of said chain, said roller entering the guide again, if the respective thread-carrier rail is to be moved in a direction opposite to the former. In this case the chain 4 which serves for the transmission of the driving motion from the slur-cock rail 1 to one of the thread-carrier rails is fastened in the above-mentioned manner on said slur-cock rail or on some other reciprocating organ of the knitting machine. The catch-member 24 forming part of a thread-carrier is thus carried with the chain 4 along the portion positioned between the two vertical portions 25 and 26 extending in downward and upward direction, respectively, and being positioned outside of the sprocket-wheels 6 and 7.

About at the center point of the chain 4 there is provided a bolt or pivot 27 which is either fastened to a link of the chain 4 or made in the form of an extension of a link pin of said chain. Mounted on said bolt or link pin is a roller 28 and in order to drive the catch-member 24 from said roller 28 two vertical extensions of ledges 29 and 30 are arranged on the latter, the distance between said extensions or ledges being equal to the diameter of said roller 28. The space between said ledges 29 and 30 opens freely above and below, so that the roller 28 may immediately come out of the range of action of said ledges, as soon as it engages with one of the two portions of the chain directed perpendicularly to the catch-member 24. The roller 28 may also again enter freely the space between the ledges 29 and 30 as soon as during the subsequent working step the chain 4 again carries back the roller 28 into the range of action of said ledges. The roller 28 may therefore be made of small length, the centers of the ledges 29 and 30 being at even height with the portion of the chain between the rollers 6 and 7.

The ledges 29 and 30 are well rounded at their upper and under ends as shown in Fig. 6 to permit the roller 28 to always easily enter the space between said ledges.

The aforescribed operating mechanism may not only be used for imparting motion to the carrier for the ground-thread and the carriers for the thread which serves to re-inforce the toe portion of a stocking, but also for the purpose of operating the carrier of the thread destined for making the heel flap. In the latter case the thread-carrier 31 which, for instance, serves to re-inforce the upper part of the heel 32 on the right-hand side of a stocking as well as the thread-carrier which on the same side of the stocking is to lay the thread for making the heel-part 33 must be adjusted only on the part A' of the series of meshes between the lateral edges of the upper part of the heel and the heel proper, this adjustment being effected by means of the roller 28 and the chain 4. As these parts A' of the series of meshes are outside of the center-line of the fabric and outside of the needles, the slides carrying the rollers 6 and 7 must be correspondingly adjusted. The roller 28 is thus positively carried always a short distance along the portions 26 and 25 of said chain through a distance appropriately greater than said former distance, said roller coming in every case out of the range of action of the ledges 29 and 30. The carriers for the thread destined for re-inforcement of the left-hand upper heel and for making the left-hand part of the heel as well as the carrier 34 for the ground thread must be driven in a similar manner.

I claim:

1. Operating mechanism for the thread-carrier rails of flat framework knitting machines, said mechanism comprising a pair of slides adjustable with respect to each other, a plurality of sprocket-wheels, said sprocket-wheels being mounted in part on said one and in part on said other slide, a driving chain laid round said sprocket-wheels permitting variation of the length of the effective portion of said chain intermediate said slides during adjustment of the latter relatively to each other, the inner sprocket-wheels on either of said slides being mounted at a height permitting free passage of said one inner sprocket-wheel on one slide past said inner sprocket-wheel on said other slide when adjusting said slides into shortest distance from each other.

2. Operating mechanism as specified by claim 1, having said inner sprocket-wheels mounted at a height permitting passage of said one inner sprocket-wheel on said one slide above and past the inner sprocket-wheel on said other slide, when adjusting said slides into their shortest distance from each other.

3. Operating mechanism as specified by claim 1, having said inner sprocket-wheels displaced with respect to each other to permit said inner sprocket-wheel on one slide to come into co-axial position with said inner sprocket-wheel on said other slide upon adjustment of said slides into their shortest distance from each other.

4. Operating mechanism as specified by claim 1, said mechanism including a slur-cock rail, said sprocket-wheels and said chain being arranged so that the two portions of said chain positioned perpendicularly to said slur-cock rail and defining standstill of the thread-carrier guide-rails are directed oppositely to each other with respect to the effective portion of said chain intermediate said inner sprocket-wheel on said one slide and said inner sprocket-wheel on said other slide.

5. Operating mechanism as specified by claim 1, said mechanism including a slur-cock rail, and adjusting means arranged to permit adjustment of at least one of said sprocket-wheels with respect to said slides obliquely to the direction of said slur-cock rail.

6. Operating mechanism as specified by claim 1, said mechanism including a slur-cock rail, and a curved track associated with at least one of said sprocket-wheels, said curved track arranged to permit adjustment of said sprocket-wheel with respect to said slides for regulating the tension of said chain.

7. Operating mechanism as specified by claim 1, said mechanism including a slur-cock rail, an adjusting lever, a curved track fixed to the frame of the machine and adapted to form a guide for at least one of said sprocket-wheels, said lever and said curved track adapted to permit adjustment of said sprocket-wheel with respect to the respective slide in accordance with the displacement of the latter.

8. Operating mechanism as specified by claim 1, said mechanism including a guide open in upward and downward direction and inserted into the portion of said chain intermediate said inner sprocket-wheels, a catch in the form of a guide-roller co-operative with said guide, said catch adapted to come out of engagement with said guide, whenever said catch during reciprocating motion of said portion of said chain arrives at a vertically directed portion of the latter.

9. Operating mechanism for the thread-carrier rails of flat framework knitting machines,

said mechanism comprising a pair of slides adjustable with respect to each other, a plurality of wheels, said wheels being mounted in part on said one and in part on said other slide, a driving member passing round said wheels permitting variation of the length of the effective portion of said member intermediate said slides during ad-

justment of the latter relatively to each other, the inner wheels on either of said slides being mounted at a height permitting free passage of said one inner wheel on one slide past said inner wheel on said other slide when adjusting said 5 slides into shortest distance from each other.

ANTON LOIMANN.
